BERYL W. ADAMS, OF TROY, MONTANA.

SIGNAL-BELL.

1,284,957.

Specification of Letters Patent. Patented Nov. 19, 1918.

Application filed October 20, 1916. Serial No. 126,772.

To all whom it may concern:

Be it known that I, BERYL W. ADAMS, a citizen of the United States, residing at Troy, in the county of Lincoln and State of 5 Montana, have invented certain new and useful Improvements in Signal-Bells, of which the following is a specification.

This invention relates to an improvement 10 in signal bells and more particularly to bells such as are adaptable for use in conjunction with mine hoists and the like to give signals to the hoist engineer, and in other similar connections, the purpose being to provide a bell by which single stroke signals 15 may be given in clear plain tones and at high speed without confusion.

An object of my invention is to provide a bell together with actuating structure therefor which is to be connected in on an alternating current circuit and is so arranged 20 that single stroke signals will be sounded irrespective of whether the energizing connection of the circuit is made of short or long duration, and to so construct the parts that 25 even when the circuit is connected in for some time no damage will result.

A further object lies in providing means in connection with the bell clapper by which the clapper will be given a sharp stroke and 30 will then be returned to a position out of contact with the bell for successive alarm or signal strokes without depending upon electromagnetic or other electrical means for the return.

35 With the above and other objects in view, my invention consists in certain novel features of construction and combinations of parts which will be hereinafter set forth in connection with the drawings and then 40 more particularly pointed out in the claims.

In the drawings:

Figure 1 is a view in front elevation of the device of my invention.

Fig. 2 is a view in side elevation.

45 Fig. 3 is a sectional view taken on the line 3-3 of Fig. 1.

Fig. 4 is a fragmentary sectional view to illustrate portions of the detail construction.

50 Fig. 5 is a vertical sectional view through the electrically operated bell striking means.

Fig. 6 is a detail sectional view to better show the arrangement of the clapper actuating means.

The supporting base structure 1 may be

constructed of wood, slate, or any other suitable material, and the gong 2 of the bell is mounted at the lower end thereof. A clapper mounting bracket 3 is secured on the base 1 above the gong 2, and the clapper 4 is mounted on this bracket 3 by means of the 55 stem 5. The stem 5 of the clapper is connected with the bracket 3 to be capable of swinging movement so that the clapper 4 may be brought into and out of striking engagement with the gong 2, and a coil spring 6 is connected between an arm 7 on the 60 stem 5 and an arm 8 formed in conjunction with the bracket 3, this coil spring acting to normally hold the stem 5 swung upwardly so that the clapper 4 is out of contact with the 65 gong 2.

A bracket is mounted on the base 1, above the clapper stem 5, and as shown this bracket comprises the base 9 continued in an arm which at the head thereof has an 70 opening 10. At a point below the opening 10, the stem 5 has a striking or anvil block 11 secured to be brought against the bracket 12 in the upward swinging movement of the stem, the parts being so arranged 75 that as a blow is struck, against the block 11, the spring 6 will be flexed sufficiently that the stem 5 will swing sharply down and in consequence the clapper 4 will be brought with a sharp stroke against the gong 2, the 80 spring 6 acting to immediately return the clapper from the striking position and to catch the same upon the rebound and hold it.

Electrically actuated means is employed 85 to strike the driving blow against the block 90 11, and this means constitutes a sleeve 13 which has the coil windings 14 thereon. Suitable connections are made from the terminal wires of the coil 14 to the circuit wires 15 and 16, which may be connected to 95 a plug socket which in turn is connected with the main line circuit wires 17 by the insertion of the plug 18 into the socket. A core 19, which is constructed as better shown in Fig. 5 is arranged within the sleeve 13 100 to be capable of limited endwise movement, a bearing ring 20 being connected with the lower end of the sleeve 13 to hold the core 19 in its proper path of movement and a ring 21 being mounted on the upper end of 105 the sleeve 13 for the same purpose. The core 19, which is of wood or other suitable material, at its upper end is preferably made

hollow and has the short wire members bunched as at 22 to form a laminated core structure which will be more readily affected by current passing through the wire of the 5 coil 14. The core 19 is reduced and made of less diameter than the interior bore of the sleeve 13, at its lower end, and a coil spring 23 is mounted between the shoulder 24 of the core and the upper side of the 10 bearing ring 20 so that the core 19 will be normally lifted by this spring 23.

A supporting bracket structure 25 is mounted above the sleeve 13 and in line therewith, and a ball or block 26 of a cushion 15 material is held in conjunction with this bracket by a clamping member 27 so that as the core 19 is forced upwardly through the action of the spring 23, the upward movement thereof will be stopped by contact 20 with the cushion member 26. It is essential that the winding of the coils 14 be such that the attractive force will be exerted to force the core 19 downwardly, and thus when a switch, button, or other circuit connection 25 in the main circuit 17 is thrown in to connect the circuit wires, the coil 14 will be energized and in consequence the core 19 will be drawn sharply downwardly against the tension of the spring 23 and will strike 30 a driving blow against the striking block 11 to impart movement to the stem 5 and will consequently bring the clapper 4 against the gong, striking a clear and plain tone. As the circuit connecting means is released, 35 the coil 14 will be deenergized and in consequence the core 19 will be again raised through the action of the spring 23 and will be brought up against the cushion member 26, or if the circuit connection is not broken, 40 then the coil 14 will remain in an energized condition and the lower end of the core 19 will be retained against the block 11, however, further striking blows of the clapper 4 will not occur as a sharp blow against the 45 anvil block is required to cause contact of the clapper with the gong. Under some circumstances it may be found desirable to introduce some means of opening the circuit when it is left closed through inadvert- 50 ence or through any other cause, and to accomplish this purpose a hot wire circuit opening means may be introduced in the wire 16 or in the wire 15, such a means being shown connected at 28 in the circuit 55 wire 16 from the plug socket to one of the terminals of the winding of the coils 14. This automatically operating circuit braking means may be of any standard form and construction, and for this reason the details 60 thereof are not herein shown and described. To permit removal of the parts of the electrically actuating means, it is desirable that the clamp member 27 be made removable so that the cushion member 26 can be displaced, 65 and the core 19 can thus be drawn vertically

upwardly from its mounting within the sleeve 13, and I therefore provide the clamp bolts 29 to retain this clamp member 27 in the position of securing the block or cushion member 26. It is of course understood that 70 the core 19 is reduced at its lower end to be received through the opening 10 of the bracket, and the bracket is placed at a height that a driving blow of the core is necessary to bring the clapper against the bell, 75 the bracket acting to hold the core against excessive downward movement.

While I have herein shown and described only one specific form of the device, it will be understood that changes and modifications might be resorted to in the form and arrangement of the parts as well as in the circuit connections thereto without departing from the spirit and scope of my invention, and hence I do not wish to be limited 85 to the exact disclosure but only to such points as may be set forth in the claims.

I claim:

1. A signal bell comprising a base structure, a gong mounted on the lower end of said base structure, a clapper having a stem pivotally mounted on the base structure, a spring to normally hold said stem raised to resiliently retain the clapper out of contact with the gong, a bracket having an opening therein mounted on the base, a striking block carried by the clapper stem to come against the bracket to stop raising movement thereof, an electro-magnetic coil arranged above the striking block, a core mounted within the coil to be capable of movement, a spring acting to normally raise said core within the coil, a cushion member mounted on the base structure to hold the core against excessive upward movement, and circuit connections arranged through the coil by which the same may be energized to cause downward travel of the core to strike through the opening in the bracket against the striking block and to impart a driving blow through the clapper stem to the clapper to cause the same to be moved against the tension of the retaining spring and to contact with the gong.

2. A signal bell of the class described comprising a base, a gong carried thereby, a clapper member supported upon said base, a spring engaging said clapper member for normally holding the same in an inoperative position, means for drawing said clapper member downwardly into operative engagement with said gong for sounding said gong, a cushion member, a bracket carried by the upper end of said base and engaging said cushion member, a retaining plate engaging the lower end of said cushion member, retaining screws carried by said bracket and for holding said retaining plate upon said bracket, and said bracket placed above said clapper for supporting said cushion member

in a proper position for engaging said clapper as said clapper returns to its normal position.

3. A signal bell of the class described comprising a base, a gong carried thereby, a vertically movable plunger supported upon said base, electro-magnetic means associated with said plunger for forcing the same downwardly, a coil spring engaging said plunger for normally urging the same upwardly, a gong sounding member located below said plunger and adapted to be engaged thereby for throwing the same into engagement with said gong, the bracket carried above said plunger, a spherical cushion member supported upon said bracket, a retaining plate, said spherical member extending through said retaining plate, and adjustable screws carried by said bracket and engaging said retaining plate for yieldably supporting said cushion member upon said base.
4. A signal bell of the class described comprising a base, a vertically movable plunger carried by said base, electro-magnetic means adapted to be energized for forcing said plunger downwardly, a gong engaging means actuated by said plunger, a bracket supported above said plunger on said base, said bracket provided with an aperture formed therein, a spherical cushion member seated partly within said aperture, a retaining plate provided with an aperture adapted to permit said spherical member to extend partly therethrough, and adjustable retaining screws carried by said bracket and engaging said retaining plate for yieldably supporting said cushion member upon said bracket.
5. A signal bell of the class described comprising a base, a gong carried thereby, a gong engaging stem supported upon said base, an anvil block carried by said stem, a guiding bracket for limiting the upward swinging movement of said stem, a plunger adapted to extend through said guiding bracket and engage said anvil block for forcing said stem into contact with said gong, a spring supporting arm carried by said base adjacent said stem, said stem provided with an upwardly extending finger, a spring engaging said finger and also engaging said arm for normally holding said stem in an inoperative position, and means for actuating said plunger.

In testimony whereof I affix my signature in presence of two witnesses.

BERYL W. ADAMS.
